UNITED STATES PATENT OFFICE.

ROBERT W. SCOTT, OF LEEDS POINT, NEW JERSEY, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

KNITTED FABRIC.

985,846.

Specification of Letters Patent.

Patented Mar. 7, 1911.

Application filed April 8, 1909. Serial No. 488,543.

To all whom it may concern:

Be it known that I, ROBERT W. SCOTT, a citizen of the United States, residing in Leeds Point, Atlantic county, New Jersey, 5 have invented certain Improvements in Knitted Fabrics, of which the following is a specification.

My invention relates to knitted fabrics composed in part of ribbed web and in part 10 of plain web, the plain web having a lesser number of wales than the ribbed web and the change being effected by doubling some or all of the rib wales into wales of the plain web.

15 Hitherto the change from one type of web to the other has been effected by laterally displacing a stitch of each wale which is to be doubled and interknitting said laterally displaced stitch with a stitch of the adjoining standing wale, but this method is objectionable because a laterally displaced stitch does not present itself in the best position 20 for the entrance of the needle to which it is to be transferred.

25 The object of my present invention has therefore been to overcome this objection in effecting such doubling transfers and at the same time to make a less abrupt change in the width of the web at the point where the 30 wider web joins the narrower web.

In the accompanying drawings—Figure 1 is an exaggerated view of a piece of web knitted in accordance with my invention, in which a change is effected from two-and-two 35 ribbed web to plain web having a lesser number of wales; Fig. 2 is an exaggerated view of a piece of web in which change is effected in accordance with my invention from a one-and-one ribbed web to plain web 40 having a lesser number of wales; Figs. 3, 4 and 5 are diagrammatic representations of the different dispositions of the needles resorted to in knitting the web shown in Fig. 1, and Figs. 6, 7 and 8 are diagrammatic representations of the different dispositions of the 45 needles resorted to in knitting the web shown in Fig. 2.

50 My invention can be practiced upon any type of rib knitting machine provided with means for shogging the needles of one set in respect to those of the other set so as to cause the needles of the two sets to assume, at different times, different relations to one another, and also provided with means

for transferring stitches from needles of one 55 set to needles of the other set, and with means for independent control of the needles in the manner hereinafter set forth.

Usually my invention will be practiced in connection with a circular rib knitting 60 machine having the needles for producing plain web contained in the cylinder and the ribbing needles contained in the dial, hence, for convenience, I will, in my specification and claims, refer to the plain web needles 65 as "cylinder" needles and to the ribbing needles as "dial" needles, without, however, intending thereby to limit myself to a machine of this type.

As an instance of a machine which, without much change is adapted for the carrying out of my present invention I may refer to that forming the subject of my Letters Patent No. 834,763, dated October 30th, 1906.

The main difference between my present 75 invention and previous inventions of its class which I have devised, is that it is not the shogged stitch which is interknitted with the standing wale but a subsequently produced stitch, the object being to permit 80 the stitch which is actually transferred to be drawn out straight over the receiving needle instead of being pulled diagonally across the same, as it must be when the transferred 85 stitch is the shogged stitch.

In carrying out my present invention one or more, and preferably a plurality, of stitches are formed upon the shogged dial needles while the same occupy their new relation to the cylinder needles and before 90 effecting the transfer of the stitches from the dial needles to the cylinder needles, and in effecting the transfer the dial needles are preferably projected to such an extent as to draw into line with the receiving needles 95 the stitches of the course preceding that actually carried by said dial needles, both the preceding stitches and those cast from the dial needles being caught by the receiving cylinder needles when said dial needles 100 are retired, this having been found in practice to be the best method of effecting the transfer, although in carrying out my invention it is not absolutely necessary to resort to this method, as but one course of ribbed 105 web may be formed upon the needles when they occupy their new relations, the stitches upon the dial needles being transferred to

the receiving cylinder needles. In either case the stitch to be transferred will, on the projection of the dial needle be drawn out directly over the receiving cylinder needle, 5 there being no tendency to lateral deflection of said transferred stitch, because the stitches upon the cylinder needles on each side of the dial needle exercise substantially the same degree of lateral pull upon the dial needle 10 stitch.

In Fig. 1, a' and b' represent the standing wales which continue throughout both the ribbed and plain webs, x' represent wales which are rib wales in the ribbed web and 15 plain wales in the plain web, and y' represent wales which appear only in the ribbed web, the wale b' being the same throughout, the rib wale y' being doubled into the standing wale a' , and the rib wale x' being doubled into a freshly started plain web wale c' .

In producing the two-and-two ribbed portions of this web the needles are disposed as shown in Fig. 3, the web being produced upon the cylinder needles a and b , and upon 25 the intervening dial needles x and y , empty and inactive cylinder needles c being interposed between the dial needles x and y of each pair.

The first step in the transfer operation is 30 to shog the needles x and y into line respectively with the needles c and a , as shown in Fig. 4, and two independent and interlocked ribbed webs are then produced, one a one-and-one rib upon the needles x and a , and 35 the other a two-and-one rib, upon the needles b , c and y . By preference, two of each of these independent courses are thus knitted, and the stitches upon the needles y as well as the stitches of the preceding course are then 40 transferred to the needles a and the like stitches are transferred from the needles x to the needles c , the needles x and y being then retired from action and plain web being knitted upon the cylinder needles a , b , and c , 45 as shown in Fig. 5.

In the web shown in Fig. 1, x^2 and y^2 represent the stitches upon the needles x and y at the time they are shogged, x^3 and y^3 stitches of the first course knitted upon the 50 needles x and y in their new relation, x^4 and y^4 stitches of the second course produced upon said needles x , y , in such new relation, and c^2 , c^3 , a^2 , a^3 and b^2 , b^3 respectively the first and second stitches formed upon the 55 needles c , a and b in the new relation, both stitches x^3 and x^4 being transferred to the needles c , and both stitches y^3 and y^4 being transferred to the needles a preparatory to the production of plain web. In this web a 60 thirty-three-and-one-third per cent. doubling is effected, that is to say the ribbed web has thirty-three-and-one-third per cent. more wales than the plain web.

In the web shown in Fig. 2 a somewhat 65 similar method of transfer is adopted in con-

nection with a web in which change is effected from a one-and-one ribbed web to a plain web. In this web a' and b' represent the standing wales which continue throughout both the ribbed and plain webs, and x' and y' the wales which appear only in the ribbed web, the wales x' being doubled into the standing wales a' and the wales y' being doubled into the standing wales b' . In producing this web the dial needles primarily 75 alternate in regular order with the cylinder needles, as shown in Fig. 6, and ordinary one-and-one ribbed web is produced upon the needles while they are in such relation.

The first step in the transfer operation is 80 to shog the dial needles, so that the needles x will be in line with the cylinder needles a , and the needles y will be in line with the cylinder needles b , as shown in Fig. 7, and two independent and interlocked ribbed 85 webs are then produced, a course of one-and-one ribbed web being first knitted upon the needles b and x , and a course of one-and-one ribbed web being then knitted upon the needles a and y , as shown in Fig. 7, each of 90 these courses being then, by preference, followed by a second course, after which, the needle stitches and those just preceding them are transferred from the needles x to the needles a , and from the needles y to the 95 needles b , the needles x and y being then retired from action and plain web being produced upon the cylinder needles a and b as indicated in Fig. 8. This produces a web in which there is a one-hundred per cent. 100 doubling, there being twice as many wales in the ribbed web as in the plain web. In Fig. 2 the stitches are designated in the same manner as in Fig. 1.

In both of the fabrics which I have shown 105 and described the stitches transferred from the dial to the cylinder needles are subsequent to the laterally displaced stitches caused by the shogging of the dial needles and each transfer is what I term a "straight" 110 transfer caused by direct outward movement of the transfer needle over the receiving needle instead of a doubling transfer effected by a compound movement of the transfer needle which shogs or laterally deflects a 115 stitch into position to be engaged by the receiving needle. In both of the fabrics shown and described, moreover, the change from one character of web to the other is effected through the medium of an intermediate web of a character different from that of either of the webs between which it is interposed; thus in the web shown in Fig. 1 the change from two-and-two ribbed web to plain web is effected through the intervention of two 120 independent webs, one a two-and-two ribbed web and the other a one-and-one ribbed web and in the web shown in Fig. 2 change from one-and-one ribbed web to plain web is effected through the intervention of two inde- 125 130

pendent one-and-one ribbed webs. By reason of the plurality of courses of stitches contained in the intervening web, the reduction in the width or diameter of the web is effected less abruptly than when the shogged stitches are directly transferred.

It will be understood that for the better showing of the structure and arrangement of some of the stitches of the various fabrics 10 which I have illustrated in the drawings, others of said stitches have been lengthened, spread, or otherwise distorted or misplaced, as compared with their character and position in the actual fabrics.

15 I claim:

1. A knitted fabric comprising two main webs, one having a greater number of wales than the other, and two independent interposed webs.
- 20 2. A knitted fabric comprising two main webs, one having a greater number of wales than the other, and two independent interposed webs, each of a character different from that of either of the main webs.
- 25 3. A knitted fabric comprising ribbed and plain main webs, and two independent interposed webs, the ribbed web having a greater number of wales than the plain web.
- 30 4. A knitted fabric comprising ribbed and plain main webs, the ribbed web having a greater number of wales than the plain web, and two independent interposed webs each of a character different from that of either of the main webs.

35 5. A knitted fabric comprising ribbed and plain main webs, the ribbed web having a greater number of wales than the plain web, and two independent interposed webs, one having excess wales doubled into wales of 40 the plain web.

6. A knitted fabric comprising ribbed and plain main webs, the ribbed web having a greater number of wales than the plain web, and two independent interposed webs, one 45 having excess wales doubled into standing wales of the plain web and other excess wales merged into newly started wales of the plain web.

7. A knitted fabric comprising ribbed and plain main webs, the ribbed web having a greater number of wales than the plain web, and two independent interposed webs in one of which excess wales have straight stitches doubled into wales of the plain web.

55 8. A knitted fabric comprising ribbed and plain main webs, the ribbed web having a greater number of wales than the plain web, and two independent interposed webs in one of which excess wales have straight stitches 60 doubled into standing wales of the plain web.

9. A knitted fabric comprising ribbed and plain main webs, the ribbed web having a greater number of wales than the plain web, and two independent interposed webs in one 65 of which excess wales have straight stitches

merged into newly started wales of the plain web.

10. A knitted fabric comprising ribbed and plain main webs, the ribbed web having a greater number of wales than the plain 70 web, and two independent interposed webs one having excess wales containing a plurality of straight stitches doubled into wales of the plain web.

11. A knitted fabric comprising ribbed 75 and plain main webs, the ribbed web having a greater number of wales than the plain web, and two independent interposed webs one having excess wales containing a plurality of straight stitches merged into stand- 80 ing wales of the plain web.

12. A knitted fabric comprising ribbed and plain main webs, the ribbed web having a greater number of wales than the plain 85 web, and two independent interposed webs one having excess wales containing a plurality of straight stitches merged into newly started wales of the plain web.

13. The mode herein described of effecting reduction in the number of wales in a 90 knitted web, said mode consisting in first knitting the web with the greater number of wales with alternating stitches, some facing in one direction and others in the opposite direction, shogging stitches of wales of one 95 face of the web into line with wales of the other face of the web, drawing stitches in said shogged wales in their new relation to form one web, drawing stitches in the wales of the other face of the web to form another 100 and independent web, and then interknitting stitches in wales of one of said independent webs with corresponding wales of the other web.

14. The mode herein described of effecting reduction in the number of wales in a 105 knitted web, said mode consisting in first knitting the web with the greater number of wales with alternating stitches, some facing in one direction and others in the opposite 110 direction, shogging stitches of wales of one face of the web into line with wales of the other face of the web, drawing stitches in said shogged wales in their new relation to form one web, drawing stitches in the wales 115 of the other face of the web to form another and independent web, and then interknitting a plurality of stitches in wales of one of said independent webs with corresponding wales of the other web.

15. The mode herein described of effecting reduction in the number of wales in a 120 knitted web, said mode consisting in first knitting the web with the greater number of wales with alternating stitches, some facing 125 in one direction and others in the opposite direction, shogging stitches of wales of one face of the web into line with wales of the other face of the web, drawing stitches in said shogged wales in their new relation to 130

form one web, drawing stitches in the wales of the other face of the web and in newly started wales to form another and independent web, and then interknitting stitches of the shogged wales with corresponding wales of the other web.

16. The mode herein described of effecting reduction in the number of wales in a knitted web, said mode consisting in first knitting the web with the greater number of wales with alternating stitches, some facing in one direction and others in the opposite direction, shogging stitches of wales of one face of the web into line with wales of the other face of the web, drawing stitches in

20 said shogged wales in their new relation to form one web, drawing stitches in the wales of the other face of the web and in newly started wales to form another and independent web, and then interknitting a plurality of stitches in each of the shogged wales with corresponding wales of the other web.

25 In testimony whereof, I have signed my name to this specification, in the presence of two subscribing witnesses.

ROBERT W. SCOTT.
